I. E. STEELE

AUTOMATIC DRAFT CONTROL

Filed March 12, 1925

Inventor

Witness

Ira E. Steele,

By *A. Williamson & Co.*

Attorneys.

UNITED STATES PATENT OFFICE.

IRA E. STEELE, OF SIOUX CITY, IOWA.

AUTOMATIC DRAFT CONTROL.

Application filed March 12, 1925. Serial No. 15,054.

To all whom it may concern:

Be it known that I, IRA E. STEELE, a citizen of the United States, residing at Sioux City, in the county of Woodbury and State 5 of Iowa, have invented certain new and useful Improvements in Automatic Draft Controls; and I do declare the following to be a full, clear, and exact description of the invention, such as will enable others skilled 10 in the art to which it appertains to make and use the same.

My invention relates to improvements in means for controlling the draft of stoves and furnaces, and it also has reference to 15 devices for admitting air into the smoke outlet passage, to by this means, check the draft.

It is the object of the invention to provide a simple and inexpensive, yet an effective and reliable automatic damper of a self-closing suction-opened type, said damper being adapted to remain closed until the draft through the smoke outlet passage reaches a pre-determined strength, where- 20 25 upon the suction created by such draft, will automatically open the damper and admit atmospheric air, so that the draft is checked.

With the foregoing in view, the invention resides in the novel subject matter herein- 30 after described and claimed, the description being supplemented by the accompanying drawing.

Figure 1 is an outer side elevation of an automatic damper constructed in accordance 35 with my invention.

Figure 2 is a vertical transverse sectional view as indicated by line 2-2 of Fig. 1.

Figure 3 is a horizontal sectional view on the irregular line 3-3 of Fig. 1.

40 In the drawing above briefly described, the numeral 1 designates a portion of a stack, chimney, or other smoke outlet from a stove or furnace, said passage having an opening 2 which is preferably rectangular. 45 Secured against the outer side of the passage 1, around the opening 2, I have shown a flat rectangular frame 3 whose upper side member is provided with a horizontal flange 4 to engage the upper edge wall of the opening, while the lower side member 5 of the frame is provided preferably with a similar flange 6 to engage the lower edge wall of the opening. The vertical side members 7 of the frame 1 are preferably provided with 50 inwardly extending vertical flanges 8 whose inner edges preferably decline toward the

inner surface of the side member 5 and merge into the latter. The inner side of this member 5 is provided, above the flange 6, with a plurality (preferably two) of integral lugs 10 which extend inwardly and upwardly, the base portions of these lugs being downwardly spaced from the upper edge of the side member 5. Preferably, the lugs 10 are inwardly spaced from the flanges 8, 65 as shown in dotted lines in Fig. 1 and illustrated also in Fig. 3.

A substantially vertical damper plate 11 is provided to close the frame 3 under ordinary circumstances, said plate preferably 70 having a sharpened lower edge 12 which rests upon the lugs 10, at their juncture with the lower side member 5 of the afore- 75 said frame. This plate is adapted to close outwardly against the inner edge of the flange 4 and the inclined edges 9 of the flanges 8, and to normally hold the plate in this position, I have provided it with a depending arm 13 whose upper end is riveted or otherwise secured to said plate, 80 as indicated at 14. The arm extends to the outer side of the frame and the passage 1, and is suitably weighted, for instance, by a weight 15 having an adjusting screw 16. When the weight is properly adjusted, while 85 it will hold the plate 11 closed under ordinary circumstances, whenever the draft through the chimney or the like is sufficient to overcome the action of the weight, the suction created by such draft will automatically swing the plate 11 inwardly as shown in Fig. 2, thus supplying a quantity of atmospheric air to the smoke outlet passage and consequently cutting down the draft, 90 with the numerous well known advantages. 95

Preferably, the plate 11 is provided with integral inwardly projecting ears 17 which engage the outer sides of the lugs 10 to hold said plate against sliding in the direction of its pivotal axis. Thus, there is no possibility of the vertical edges of the plate scraping on the vertical edges of the openings 2 and interfering with proper opening and closing of said plate. 100

As excellent results are obtainable from 105 the details disclosed, they are preferably followed. However, within the scope of the invention as claimed, modifications may of course be made.

I claim:

1. An automatic damper for a stove or furnace smoke outlet passage having an air

inlet opening, said damper comprising a frame whose lower side member is provided with a plurality of horizontally spaced lugs which extend inwardly and upwardly from 5 said member, a plate having a sharpened lower edge adapted to pivotally rest on said lugs, a weighted arm secured to the outer side of said plate and projecting below the same in a plane parallel thereto, and inwardly projecting ears on said plate, engaging 10 said lugs to hold the plate against sliding in the direction of its pivotal axis.

2. An automatic damper for a stove or furnace smoke outlet passage having an air inlet opening comprising a frame having upper and lower horizontal flanges and vertical 15 side flanges the inner edges of which decline

outwardly from the top to the bottom of the frame, horizontally spaced lugs, extending inwardly and upwardly from the inner side 20 of the lower portion of said frame, a plate having its lower edge pivotally resting on said lugs and adapted to engage the declined edges of said side flanges of the frame when the plate is in closed position and a weighted arm secured to the outer side of said plate, and projecting below the same in a plane parallel thereto, whereby the plate is normally held in closed position against the 25 declined edges of the side flanges of the frame.

In testimony whereof I have hereunto affixed my signature.

IRA E. STEELE.
